UNITED STATES PATENT OFFICE

OSCAR D. GIBBS, OF ROCHESTER, NEW YORK, ASSIGNOR OF ONE-THIRD TO ERIC ISCHINGER, OF EAST ROCHESTER, NEW YORK

STAPLING MACHINE

Application filed January 14, 1929. Serial No. 332,468.

This invention relates to stapling machines and has for its object to provide a machine with which the heads of barrels may be stapled in place into the ends of the barrels or perform similar operations on containers in which it is desired to fasten the cover in place within the container.

Another object of this invention is to so construct the machine that it can be readily and easily handled by its operator and considerable time saved by him in fastening the heads into the barrels over the old method of nailing the barrel heads in place.

Another object of this invention is to drive the staples in place in the barrel and barrel head so that they can be readily and quickly removed with a suitable tool when it is desired to remove the head from the barrel.

Another object of this invention is to so construct the stapling machine that it will clamp itself automatically in place on the barrel or container while a staple is being driven into the barrel or container.

Another object of this invention is to so construct the machine that it will automatically release itself from the barrel or container as soon as a staple has been driven in place by it and the operating lever moved to its starting position ready to drive the next staple.

Another object of this invention is to provide a magazine for the staples into which a new supply of staples can be readily and quickly placed.

Another object of this invention is to provide a staple in the stapling machine having nail points so that the staple when driven in place by the stapling machine follows a straight path and can be driven into the narrow edge of a barrel head or other cover without danger of having one or both of the prongs of the staple deflected either above or below the barrel head.

All these and other objects of this invention will be apparent from the accompanying

drawings, the specification and the claims at the end thereof.

In the accompanying drawings:

Figure 1 is a side elevation of the stapling machine partly broken away and positioned on the chime of a barrel illustrated in section, the machine being ready to drive a staple thru the barrel hoop and barrel stave into the edge of the barrel head. 50

Figure 2 is a front elevation of the upper portion of the staple magazine of the stapling machine. 55

Figure 3 is a rear elevation of the upper portion of the staple magazine of the stapling machine.

Figure 4 is a horizontal sectional view thru the staple magazine of the stapling machine, the section being taken on the line 4x—4x of Figure 3. 60

Figure 5 is a top plan view and partial section of the stapling machine as it appears positioned on the chime of a barrel after the operating lever has been moved to drive a staple into the barrel head. 65

Figure 6 is a vertical sectional view of the stapling machine, the section being taken on the line 6x—6x of Figure 1. 70

Figure 7 is a vertical sectional view of the stapling machine, the section being taken on the line 7x—7x of Figure 1. 75

Figure 8 is a side elevation of a modified form of the stapling machine.

Figure 9 is a side elevation of another modified form of the stapling machine, parts of the machine being broken away to show the operating mechanism thereof. 80

Figure 10 is a top plan view of the modified stapling machine illustrated in Figure 9.

Figure 11 is a perspective view of one of the staples used in the stapling machines. 85

Figure 12 is a side elevation of a slightly modified form of the stapling machine.

In the several figures of the drawings like reference numerals indicate like parts.

The stapling machine forming the sub- 90

ject matter of this invention is adapted especially for use in stapling the heads into the barrels, something which has heretofore been done entirely by nailing. The nails were driven from the outside of the barrel thru the barrel hoops and staves into the edge of the barrel head but usually only one out of three nails would find its way into the edge of the barrel head, the others being driven either above or below the head which would make them practically useless for holding the head in place in the barrel. Many more nails than are needed are thus always used when fastening a head into a barrel by means of nails. In addition to the waste in nails there is also a waste of time necessary for driving the extra nails. Driving unnecessary nails furthermore tends to split the wooden barrel hoops and when the barrel head is to be removed increases the work because nails are difficult to remove, especially after their heads have been damaged, so that many times it is found necessary to destroy part of the chime of the barrel before the head can be removed.

The use of staples in place of nails reduces the number of fasteners needed to hold the head in place and also makes it possible to remove the head much quicker and easier and without destroying the chime of the barrel or a portion of it or the head itself.

The use of the stapling machine for driving the staples in addition reduces the time for fastening the head in place and makes the driving of the staples positive so that every staple is a positive fastener even when driven in place by an unskilled workman, as such a man may operate the stapling machine when he cannot handle a hammer to drive a nail straight.

The stapling machine comprises the head 1 in which the throat 2 is provided in the form of a recess which extends into the head from the bottom thereof. The head itself is made up of a pair of parallel sides 3 and 4 which are suitably held together and on one side of the throat supports the staple driver 5 and its operating mechanism and on the other side of the throat the clamping jaw 6 and its operating mechanism.

In the head section which supports the driver 5 a bottom 7 is provided and in this bottom is formed the guide channel 8. The vertical guide rib 9 on the under side of the driver 5 engages into this channel and guides the driver in a straight line in its movement back and forth. At the rear the driver is built up and from it extend a pair of horizontal guide ribs 10 and 11 which project into and thru corresponding guide slots provided in the sides of the head. To the guide ribs 10 and 11 are pivoted the links 14, 14 which in turn are pivoted to the operating lever 15 at 16. The operating lever is pivoted to the movable base 17 which is slotted at 18 and ex-

tends into the head of the machine and bolts 19 and 20 project from one side of the head to the other and pass thru the slot 18 and guide the movement of the base 17 in a straight line during a limited movement back and forth on the head.

Fastened to the bottom of the base 17 at the forward end thereof is the clamping jaw 6. This clamping jaw comprises a thin flat blade having the shape of a segment with the curved edge thereof beveled toward the bottom to form a sharp edge that can engage the chime of the barrel to hold the stapling machine in place on the barrel while a staple is driven in place.

The successive positions of the operating lever in first clamping the stapling machine in place on the chime of the barrel and then operating the driver to force a staple thru the barrel hoop and barrel stave into the barrel head are indicated by numerals I, II, and III of which the clamping position II is shown in full lines in Figure 1, while both the starting position and final position of the lever are shown in dotted lines. The full line position of the lever 15 in Figure 5 is that which corresponds with the dotted line position III of Figure 1.

When the operating lever 15 is placed in the starting position I the base 17 has been slightly moved to the right in order to withdraw the sharp edge of the clamping jaw from the throat opening 2 and allow the chime of the barrel to enter thereinto. The stapling machine is then supported on the head 21 to be fastened into the barrel by the base 17 and the clamping jaw 6. These two members of the machine when resting on the head 21 also serve to gauge the vertical position of the stapling machine by supporting the driver in the proper elevation with relation to the elevation of the head in the barrel so that when the staple is driven in place by the driver it is forced into the center of the head or very nearly so and not above or below it.

The first movement of the operating lever from I to II moves the base 17 and with it the clamping jaw 6 to the left until the sharp beveled edge of the clamping jaw engages the inside of the chime of the barrel. When engaging the chime from the inside the jaw 6 draws the opposing side of the throat opening 2 against the outside of the barrel and the barrel hoop 22 surrounding it, which results in a firm hold of the head of the stapling machine on the chime of the barrel.

The next movement of the operating lever 15 from position II to position III drives the staple in place by drawing the links 14 and with them the rear of the driver 5 to the right. The links 14 also swing downwardly during the rearward motion but the driver 5 moves in a straight line due to the guide members that are associated therewith and engage the

guide slots and guide channel provided in the head, as above described.

The lowermost staple in the staple magazine normally rests on two parallel shoulders 23 and 24 provided on each side of the guide channel 8 at the end facing the throat opening. The connecting section of the staple bridges the guide channel between the shoulders 23 and 24 so that the forward concaved end of the driver 5 engages this straight connecting section of the staple the full length of it. On the movement of the driver toward the throat opening of the machine, the staple is thus embraced on the sides, supported at the bottom and engaged the full width at the rear to insure a straight movement of the staple from which it cannot deviate while it enters the hoop, stave and barrel head.

The magazine of the stapling machine comprises a pair of uprights 25 and 26 which are fastened to the inside of the head of the stapling machine at the lower end thereof and extend down to the bottom member 7 thereof as illustrated in Figure 6. At suitable intervals the brackets 27 and 28 embrace the uprights 25 and 26 and space and hold them with relation to each other above the head of the stapling machine. Intermediate of the uprights 25 and 26 is the vertical guide bar 29 which is held intermediate of the vertical members by the brackets 27 and 28 in order to provide space on each side of the guide member to have the parallel sides of the staple engage between the uprights and the guide member and permit their moving down between them. The staples are inserted into the magazine by placing them in a straddling position over the guide member 29 and between the uprights 25 and 26 as illustrated in the several figures of the drawings. The staples are held in place in this position by the vertical locking rod 30 which carries at the upper end the head 31 and at the lower end the horizontal pin 32. On the locking rod 30 is mounted to slide the follower 33 and between the follower 33 and the head 31 the rod is surrounded by the expansion spring 34. The locking rod is placed in position in the rear of the staples after the staples have been placed into the magazine by first inserting the lower end thereof into the recess 34A while the follower 33 is placed on top of the uppermost staple in the magazine. At the same time the lower end of the locking rod is placed into the recess 34A, an extension 35 of the guide member 29 engages into a hole in the head 31 so that the rod 30 is held both at the top and bottom at a predetermined distance from the magazine which allows the staples to move down in the magazine but prevents them from dropping out therefrom.

The pressure of the expansion spring 34 on the follower 33 moves the staples whenever the lowermost of them has been removed by the driver of the stapling machine and has

moved back to its starting position to allow the next one to take its place. In this way the staples in the magazine are under a constant pressure that will insure a proper feed of the staples just as fast as the staples are forced out of the magazine and driven into the barrel head.

To hold the locking rod in place after it has been inserted, as above described, an inverted U-shaped latch 36 is pivoted to the extension 35 so that it can be swung from the dotted line position in Figure 1 to the full line position thereof to embrace the head 31 and hold it down into engagement with the extension 35 until it is desired to withdraw the rod for the purpose of refilling the magazine with staples.

The stapling machine so far described is provided with a movable clamping jaw and this construction allows the use of the stapling machine on barrels having either steel hoops or wooden hoops. The wooden hoops are considerably thicker than the steel hoops and the throat opening into which the chime of a barrel having a wooden hoop on the outside is to be inserted must of course be wider than the throat opening into which the chime of a barrel having a steel hoop is to be inserted. The movable clamping jaw described in connection with the stapling machine permits the use of a large throat opening suitable for both wooden and steel hoops.

However, should it be desirable to make two types of stapling machines, one for the steel hooped barrel and the other for the wooden hooped barrel, either a large or a small throat opening can be used in connection with a stationary jaw 40. Such a construction is illustrated in Figure 8. The construction illustrated in this figure does away with the link which connects the operating lever with the driver, as the operating lever 41 is directly connected to the driver at 42, while the lower end of the operating lever is pivoted to the head of the stapling machine by means of the link 43. Of course the operating lever must be made forked in order to straddle the head of the machine and engage the driver on each side as described in connection with the machine illustrated in Figure 1. The lower end of the forked operating lever is thus hinged to the head by a pair of links 43, one on each side of the head of the machine.

Building the machine in the manner illustrated in Figure 8 has the further advantage in that a longer leverage is provided so that less power is needed to drive the staples in place. Furthermore the tendency for the head, while moving the operating lever, is to hold the head down onto the chime instead of lifting it up as is the case with the arrangement of the lever on the machine illustrated in Figure 1. The machine illustrated in Figure 8 thus clamps itself in place.

as soon as the staple is driven into contact with the outside of the hoop of the barrel because the pressure exerted against the staple will also draw the clamping jaw against the inside of the chime so that any possible disengagement or movement of the head of the stapling machine is prevented as soon as the staple begins to enter the hoop of the barrel.

In Figures 9 and 10 the machine has been modified to drive a staple into the inside of the chime from the inside of the barrel just above the head in order to form a series of lugs on the inside of the chime that keep the head from raising up out of the barrel after it has once been placed in position therein. In this form of the machine, the driver and magazine are located to the right of the throat opening of the head of the machine or on the inside of the barrel when the stapling machine is placed on top of it.

In the machine illustrated in Figures 9 and 10 the head 50 thereof has the throat opening 51 which extends into it from the bottom as in the other stapling machines but instead of the clamping jaw the throat opening has an anvil block 52 on one side against which the points of the staple is forced thru the chime of the barrel and the hoop surrounding it and prevents these points from projecting from the hoop or turns these points over on the outside of the hoop so that in either case no sharp points from the staples can injure any one coming in contact with the hoop into which the staples have been driven.

The thickness of the anvil block can be decreased by the removal of the auxiliary block 53 which consists of a steel bar that is inserted into the head between its sides and is suspended therein by the engagement of the pin 54 into the hole 55 provided in the steel bar. The bar is held in the position in which the pin 54 engages into the hole 55 by the spring 56 mounted on one side of the bar and yieldingly resting against the pin 57 so that yielding pressure of the spring forces the bar against the anvil block proper, as illustrated in the drawings. When it is desired to remove the auxiliary block it is swung to the right into the dotted line position shown in Figure 9 against the pressure of the spring. Such a movement disengages the pin 54 from the hole in the block 53 and allows it to be withdrawn from between the head of the machine. The auxiliary block is withdrawn whenever the head of the stapling machine is positioned over the chime of the barrel at the points where the ends of the wooden hoop overlap each other and thus increase the thickness of the hoop at this point to almost twice the thickness of the hoop proper.

The driver 58 of the stapling machine is mounted to slide back and forth below the magazine 59 of the machine in practically the

same way as is described in connection with the drivers of the stapling machines illustrated in Figures 1 and 8 except that the driver is located very close to the top surface of the barrel head in order to drive the staple into the chime directly above the upper surface of the barrel head. A portion of each staple after being driven into the chime is allowed to project from the chime and these projecting portions of the staples on the inside of the chime form shoulders which hold the barrel head in place in the barrel below the chime as illustrated in Figure 9.

The driver 58 is operated by the forked operating lever 60 which is pivoted to the outer end of the links 61, 61, that in turn are pivoted to the side of the head of the stapling machine at 62. The operating lever is connected to the driver at 63 so that on the movement of the lever from the dotted line position to the full line position the lowermost staple in the magazine is forced from beneath the magazine into the inside of the chime and thru the barrel stave and barrel hoop against block 52 or 53. As the staple is forced into the chime the anvil block is at the same time drawn against the outside of the barrel hoop so that the points of the staples cannot be forced thru the barrel hoop but are stopped by the anvil block or turned over in the barrel hoop.

The sides of the head of the stapling machine, illustrated in Figures 9 and 10, extend to the rear and spread so as to form a wide base that will support the machine in an upright position when placed on top of the barrel head. While the lowermost staple is held slightly above the barrel head as long as it is located in the magazine it tilts down against the surface of the head as soon as it is driven from the magazine and enters the chime directly above the surface of the head of the barrel and not a distance from it.

The staples used in the stapling machines, above described, are formed as illustrated in Figure 11. An inspection of this figure will show that the staple is provided with nail points 65, 65 instead of the customary wedge shaped points that are provided on all staples at the present time. This deviation from the wedge shaped point to the nail point in this staple is important as it has been found that wedge shaped pointed staples will not work as well in the stapling machine for the purpose of fastening a barrel head in place; in fact, in some cases will not work at all. This is due to the fact that the staple must be driven into the edge of a thin board which is also beveled to form a wedge shaped edge which will enter and fit into the triangular channel formed on the inside of the barrel below the chime thereof. The nail pointed staple, when forced against this wedge shaped edge of the barrel head, will enter it

despite the beveled surfaces of the edge, while a wedge shaped pointed ends of a staple will be deflected by the beveled edge of the barrel head and either project above the top or below the bottom of the head without entering it.

I claim:

1. A stapling machine comprising a head having a throat opening extending into the bottom of it, a driver in said head on one side of said throat opening and below it, means for positioning a staple in said head in front of said driver to have said driver force a staple into a pair of elements, one of which projects into said throat opening and the other of which is located below said opening while at the same time drawing the opposite side of the throat opening against the back of the element projecting thereinto, and a supporting member projecting rearwardly from said head above said driver to rest on one of the elements to be stapled and support said head with its driver in line with this element on which the head is supported.

2. A stapling machine having a head with a throat opening extending into the bottom of it, a driver in said head on one side of said throat opening and below it, a gripping jaw supported by said head on the opposite side of said throat opening, means for positioning a staple in said head in front of said driver to have said driver force said staple into the front of a pair of elements, one of which projects into said throat opening and the other of which is located below said throat opening and draw said gripping jaw against the back of the element on the engagement of said staple with the element projecting into said throat opening, and a supporting member projecting rearwardly from said head above said driver to rest on one of the elements to be stapled and support said head with its driver in line with this element on which the head is supported.

3. A stapling machine having a head with a throat opening extending into the bottom of it, a driver in said head on one side of said throat opening and below it, a gauging member on said head on the other side of said throat opening adapted to decrease the width of the throat opening in relation to the thickness of the element projecting into the throat opening, and means for operating said driver to force a staple into the element from the opposite side of the gauging member below the throat opening.

4. A stapling machine having a head with a throat opening extending into it, a driver mounted in said head on one side of said throat opening and below it, a combined gauging member and gripping jaw on said head on the opposite side of said throat opening, means for positioning a staple in front of said driver to have said driver force the staple into the outside of an element located

in the throat opening and into the end of an element located below said throat opening and extending from the inside of said first element while drawing the gripping member against the inside of the first element located in the throat opening, and a supporting member projecting rearwardly from said head above said driver to rest on one of the elements to be stapled and support said head with its driver in line with this element on which the head is supported.

5. A stapling machine for stapling barrel heads into barrels comprising a head, having a throat opening extending into it, a driver mounted in said head on one side of said throat opening and below it, a gripping member carried by said head and located on the opposite side of said throat opening, a staple magazine carried by said head and means for feeding staples from said magazine in front of said driver, means for operating said driver to force one staple at a time into an element projecting into the throat opening and into an element located below said throat opening while at the same time engaging said gripping member with said element projecting into said throat opening to hold said stapling machine fastened to the element while a staple is driven into both of said elements by the driver, and a supporting member projecting rearwardly from said head above said driver to rest on one of the elements to be stapled and support said head with its driver in line with this element on which the head is supported.

6. A stapling machine for stapling barrel heads into barrels comprising a head having a throat opening extending into it, a driver mounted in said head on one side of said throat opening and below it, means for locating a staple in front of said driver, means for simultaneously operating said driver in said head and forcing said head against the rim of the barrel and holding said head in place on the rim while the driver forces the staple into the barrel below the rim into the edge of the barrel head, and a supporting member projecting rearwardly from said head above said driver to rest on one of the elements to be stapled and support said head with its driver in line with this element on which the head is supported.

7. In a stapling machine for stapling the heads of barrels into the chime thereof the combination of a supporting base adapted to rest on the head of the barrel, staple driving means supported by said base on the outside of the barrel and means for simultaneously forcing said base down onto the barrel head within the barrel and operating said staple driving means to drive a staple into the edge of the barrel head below said base from the outside of the barrel.

8. In a stapling machine for stapling the heads of barrels into the chimes thereof the

combination of a supporting base, a jaw on said base, and staple driving means supported by said base at a point opposite to but below said jaw to drive a staple into the barrel and the rim of the barrel head located within it from the outside of the barrel at a point below said jaw, said staple driving means operating to simultaneously drive the staple into the barrel in one direction while drawing said jaw against said barrel in the opposite direction and prevent the raising of said base from the barrel head during the driving operation.

9. In a stapling machine for stapling the heads of barrels into the chimes thereof, the combination of a base adapted to rest on the barrel head within the barrel, staple driving means supported by said base on the outside of the barrel approximately in line with the barrel head on which said base is supported, and an operating lever pivoted on said base and connected to said staple driving means to drive a staple on the downward motion of said lever and to hold said base in place on said barrel head while a staple is being driven into the edge of the barrel head below said base.

10. In a stapling machine for stapling the heads of barrels into the chimes thereof, the combination of a base, a jaw on said base adapted to engage the inside of the barrel above the head, and staple driving means supported by said base on the outside of said barrel, said staple driving means operating to draw said jaw against the inside of the barrel on the driving of a staple and position said base and staple driving means in a radial position with relation to the barrel and barrel head.

11. In a stapling machine for stapling barrel heads into the chimes of barrels the combination of a base, a laterally adjustable jaw mounted on said base, and staple driving means supported by said base opposite to said jaw and below it so as to drive the staple into the barrel head below said jaw while drawing said jaw against the inside of the barrel on the operation of said staple driving means, said laterally adjustable jaw being adapted to increase and decrease the distance between the edge of said jaw and said staple driving means.

12. In a stapling machine for stapling barrel heads into the chimes of barrels the combination of a base adapted to rest on the barrel head, a frame supported on said base and projecting outwardly and downwardly thereof with a throat opening between said base and the downwardly projecting portion of said frame, a staple driving member mounted in said frame in a plane approximately parallel to and below the plane of said base, and an operating lever pivoted on said frame and connected to said driving member to move

said driving member on the swinging of said operating lever toward said base.

13. In a stapling machine for stapling barrel heads into barrels the combination of a base, adapted to rest on the barrel head within the barrel, an overhanging frame at the front of said base overhanging the barrel, a rearward extension at the back of said base, a driving member mounted in said overhanging frame, a staple magazine projecting upwardly from said overhanging frame, staple feeding means in said magazine, and an operating lever pivoted on said overhanging frame and connected to said driving member and adapted to swing toward said base and the rearward extension thereof to hold the barrel head down in the barrel and said base on top of it while a staple is being driven into the edge of the barrel head.

14. In a stapling machine for stapling barrel heads into barrels the combination of a base adapted to rest on the barrel head, an overhanging frame supported on said base overhanging the barrel, a driving member mounted to slide in said overhanging frame, a magazine supported by said overhanging frame, and a bifurcated lever pivoted to said overhanging frame with said driving member located between the bifurcation and connected thereto, said bifurcated lever straddling said overhanging frame and said magazine to permit said bifurcated lever to swing rearwardly and downwardly toward the base and the barrel head while driving a staple from said magazine into the barrel head.

15. In a stapling machine for stapling barrel heads into barrels the combination of a base adapted to rest on said barrel head within the barrel, a frame supported by said base overhanging the barrel and projecting outwardly therefrom, staple driving means mounted in said outwardly projecting frame, and an operating lever for said staple driving means pivoted on said frame so as to swing down towards said base and over the barrel head on which it rests to permit the operation of said driving means from the rear and side of the barrel.

16. In a stapling machine for stapling barrel heads into barrels having a flange projecting above the barrel head, the combination of supporting means adapted to rest on the barrel head within the flange of the barrel, staple driving means and means on the outside of the flange of the barrel substantially in line with said barrel head on the inside of the flange of the barrel for operating said staple driving means, said staple driving means cooperating with said supporting means to hold said stapling machine in a predetermined position on the barrel head and clamp it to the barrel flange surrounding the barrel head on the operation of the means for operating said staple driving means.

17. In a stapling machine for stapling two members together at right angles to each other the combination of staple driving means, a swinging lever for operating said staple driving means, a supporting member for supporting said staple driving means on one of the members to be stapled and a rearward extension provided on said supporting member to form a brace for said supporting member to brace it against the movement of said swinging lever down toward said rearward extension and the member supporting it on the operation of said staple driving means.
